Patented Aug. 29, 1922.

George Cawthon, Inventor

By John P. Dohore Attorney

UNITED STATES PATENT OFFICE.

GEORGE CAWTHON, OF REDWOOD, CALIFORNIA.

DESIGN FOR A LIGHTING FIXTURE.

61,408.

Specification for Design.

Patented Aug. 29, 1922.

Application filed January 24, 1922. Serial No. 342. Term of patent 7 years.

To all whom it may concern:

Be it known that I, GEORGE CAWTHON, a citizen of the United States, residing at Redwood, in the county of San Mateo and State of California, have invented a new, original, and ornamental Design for a Lighting Fixture, of which the following is the accompanying drawing, forming part thereof.

The figure is a perspective view of a lighting fixture, showing my new design.

I claim:

The ornamental design for a lighting fixture, as shown.

GEORGE CAWTHON.
